ELCHANAN ECHIKSON, OF NEWARK, NEW JERSEY

KNIFE TANG

Application filed August 15, 1930. Serial No. 475,588.

The present invention relates to improvements in cutlery and has reference more particularly to a tang construction.

One of the important objects of the present invention is to provide an implement that is formed with a handle receiving tang at one end, the tang being of such construction as to afford maximum strength to the blade and eliminate points of critical weakness which result from sharp changes in section, and further eliminating any possibility of the tang breaking, the tang at the same time obviating the necessity of having to employ additional reinforcing means for the handle.

15 A further object is to provide a knife tang wherein the same will be of balanced proportion thus distributing the stress entirely throughout the tang and strengthening the blade of the implement itself.

20 A further object resides in the provision of a knife tang wherein the same is formed with a means for positively securing a bolster thereon at the juncture of the tang with the blade.

25 Another important object is to provide a tang construction which is simple, inexpensive, strong and durable and further well adapted for the purposes for which it is designed.

30 Other objects and advantages of the present invention will become apparent from the following description when taken in connection with the accompanying drawings.

In the accompanying drawings wherein 35 like reference characters designate corresponding parts throughout the several views:

Figure 1 is a detail perspective view of a knife blade formed at one end with my improved tang, and showing the bolster soldered on the tang at its juncture with the blade,

Figure 2 is a similar view without the bolster and more clearly illustrating the cut-out portion for receiving the solder or other fastening means provided for the bolster, and

45 Figure 3 is a longitudinal sectional view through the tang taken approximately on the line 3-3 of Figure 2.

In the drawings wherein for the purpose of 50 illustration is shown the preferred embodiment

of my invention, the numeral 1 designates a knife blade, the same being formed at its rear end with my improved tang that is denoted generally by the numeral 2. The tang is of uniform thickness throughout its 55 length and the forward end portion 3 is of greater width than the rear end portion 4, the longitudinal edges of the tang being knurled or serrated as indicated at 5, to provide a means for positively securing the tang 60 within a suitable socket provided therefor in the handle shown in the dotted lines in Figure 1.

The enlarged forward end portion 3 of the tang is preferably twice as wide as the 65 rear end portion 4 and the purpose thereof is to distribute the strength evenly thus eliminating possibility of the tang becoming broken. The enlarged forward end portion 3 of the tang is formed with a substantially circular cut-out portion 6 and extending in diverging relation from the rear side of this cut-out portion are the slightly curved channels 7 and 8, respectively. The purpose of the cut-out portion 6 and the communicating channels 7 and 8 will be hereinafter more fully described.

70 Adapted to be secured on the tang 2 at its juncture with the blade 1 is the bolster 9, and this bolster is rigidly secured in position 75 through the medium of solder or any like material that builds up the cut-out portion 6 as well as the channels 7 and 8 as indicated more clearly in Figure 1. The solder is represented at 10.

75 The rear face of the bolster is of such construction that its shape corresponds exactly to the shape of the forward end of the handle that is secured on the tang 2, thus eliminating the necessity of machining in order to make 80 the two surfaces correspond exactly when the handle is assembled on the tang. The outer surface of the bolster is of such shape as to form a continuation of the outer surface of the handle in which the tang is secured thus 85 obviating the necessity of having to machine or grind the bolster or the handle to make the outer surfaces thereof continuous or flush with each other.

90 While I have shown the tang as being par- 100

ticularly adapted for association with a knife blade, the same can be equally as well used for securing a handle to any other kind of tool in a positive and efficient manner.

5 While I have shown a preferred embodiment of my invention, it is to be understood that minor changes in the size, shape and arrangement of parts may be resorted to without departing from the spirit of the invention
10 and the scope of the appended claims.

Having thus described the invention what I claim is:

15 1. In combination with a blade, a tang formed on the rear end thereof and comprising a body portion of uniform thickness, the forward end portion of the body being of greater width than the rear end portion, a bolster mounted on the forward end portion of the tang at its juncture with the blade, the
20 forward end portion of the tang being provided with a cut-out portion for the reception of solder to secure the bolster in a rigid manner.

25 2. In combination with a blade, a tang formed on the rear end thereof and comprising a body portion of uniform thickness, the forward end portion of the body being of greater width than the rear end portion, a bolster mounted on the forward end portion of the tang at its juncture with the blade, the forward end portion of the tang being provided with a cut-out portion for the reception
30 of solder to secure the bolster in a rigid manner, said tang being formed with solder receiving channels that extend rearwardly from the cut-out portion and communicating therewith.

In testimony whereof I affix my signature.
ELCHANAN ECHIKSON.
